UNITED STATES PATENT OFFICE

116,308

DESIGN FOR A BUMPER GUARD

William C. Huber, Chicago, Ill.

Application May 23, 1939, Serial No. 85,168

Term of patent 14 years

To all whom it may concern:

Be it known that I, William C. Huber, a citizen of the United States, residing at 6630 South Minerva, Chicago, in the county of Cook and State of Illinois, have invented a new, original, and ornamental Design for Bumper Guards, of which the following is a specification, reference being had to the accompanying drawing, forming part thereof.

In the drawing,

Fig. 1 is a front elevational view of a bumper guard showing my new design;

Fig. 2 is a right side elevational view of Fig. 1;
Fig. 3 is a top plan view of Fig. 1; and
Fig. 4 is a sectional view on the line 4—4 of Fig. 1.

I claim:

The ornamental design for a bumper guard, as shown.

WILLIAM C. HUBER.
